UNITED STATES PATENT OFFICE.

JOHN A. MOORE, OF WHEELING, WEST VIRGINIA, ASSIGNOR TO WARWOOD TOOL COMPANY, OF WHEELING, WEST VIRGINIA, A CORPORATION OF WEST VIRGINIA.

TAMPING-BAR.

964,671.

Specification of Letters Patent. Patented July 19, 1910.

Application filed April 23, 1909. Serial No. 491,750.

To all whom it may concern:

Be it known that I, JOHN A. MOORE, a citizen of the United States of America, and resident of Wheeling, county of Ohio, State 5 of West Virginia, have invented certain new and useful Improvements in Tamping-Bars, of which the following is a specification.

This invention relates to tamping bars, and more particularly to an instrument of 0 that class employed in driving the tamping upon the charge in a blast-hole.

The primary object of this invention is to provide a simple and inexpensive connecting means for the rod and tamping head of 5 a tamping bar.

A further object is to provide connecting or uniting means for the rod and tamping head which will indicate to an observer the depth to which the rod is seated within the 0 head.

As is well known, a tamping head of copper or other non-spark emitting or producing material must be employed in driving the tamping upon an explosive charge in 5 order to effectually guard against a premature explosion of the charge; and, since copper is relatively more expensive than iron or steel, it is the usual practice to cast a copper head upon the end of a steel rod 0 or handle member. To comply with the requirement of the law in some States, the steel rod must terminate within a specified distance of the tamping-end of the tamping head.

For the purpose of facilitating inspection 5 of the instrument and to clearly indicate the depth to which the rod penetrates the tamping head, a terminal for said rod is provided in the present invention whose lateral edges 0 are exposed to view throughout its length.

The invention consists in the particular construction, arrangement and combination of parts which will hereinafter be fully described, reference being had to the accompanying drawings, forming part of this 5 specification, in which—

Figure 1 is side elevation of the invention; Fig. 2 is a partial longitudinal sectional view of the same; Fig. 3 is a sectional view 0 on the line 3—3, Fig. 2; and Fig. 4 is a detail perspective view of the uniting means formed on the rod or handle member.

Referring to said drawings, in which like reference numerals designate like parts

throughout the several views—1 indicates 55 the rod or handle member of the device, the same being formed of any preferred material, such as iron or steel, and 2 designates the cylindrical copper tamping head. The rod 1 has a reduced portion or neck 3 at 60 one end, and this neck is terminated by an integral flat blade 4 of substantially rectangular form which is preferably of even width throughout and slightly tapered, as shown. The width of the blade equals the 65 diameter of the body portion of the cylindrical head 2 so that, when the head is formed thereabout, the lateral edges of the blade are exposed to view, as is clearly shown in Figs. 1 and 2. Said blade has 70 therein one or more orifices or apertures 5 adapted to be filled by the metal of the head when cast thereon, a complete tie or bond being thus afforded whereby the rod and head are rigidly connected. The neck 3 is 75 wholly inclosed by the copper head, as shown, the rear portion of said head being tapered rearwardly to the junction of the rod-body with said neck. The side of the tamping-head 2 is provided with the usual 80 longitudinal groove 6 which admits of the operation of the tamping bar over the pointer which is employed to maintain an open passage to the charge for the insertion of the fuse.

Having thus described my invention, what I claim as new, and desire to secure by Letters Patent, is—

A tamping bar comprising a tamping head and a handle member, said head and member being composed of different metals and rigidly united, one end of the former being cast about one end of the latter, the uniting means comprising a reduced neck portion borne by the handle member, and a substantially rectangular integral blade terminating said portion, said blade being of less thickness than said neck portion, and of even width with the diameter of the tamping head, said head being cast to wholly inclose 95 said neck and to inclose all but the lateral edges of said blade.

In testimony whereof I affix my signature in presence of two subscribing witnesses.

JOHN A. MOORE.
